BEVERAGE VENDING MACHINE

Melvin H. Boldt, 933 N. Glenayre Drive, Glenview, Ill.,
and Thurber H. Morrison, 706 Brown Ave., Evanston, Ill.

Filed Nov. 9, 1961, Ser. No. 67,456

Term of patent 7 years

(Cl. D52—3)

FIG. 1

FIG. 2

The undisclosed side of said beverage vending machine is substantially the same in appearance as the side shown in FIGURES 2 and 4 and the rear is plain.

We claim:

The ornamental design for a beverage vending machine, as shown and described.
